[57] CLAIM

The ornamental design for a projection television console, substantially as shown and described.

DESCRIPTION

FIG. 1 is a front and left side perspective view of a projection television console showing my new design.

FIG. 2 is a front elevational view thereof; and

FIG. 3 is a left side elevational view thereof, the right side being a mirror image thereof.

The rear of the console is plain.

FIG. 1FIG. 2FIG. 3
